(57) **CLAIM**

The ornamental design for a child snack and play travel lap tray, as shown and described.

DESCRIPTION

FIG. 1 is a front isometric view of the child snack and play travel lap tray of the present invention;

FIG. 2 is a front view of the invention of FIG. 1;

FIG. 3 is a back view of the invention of FIG. 1;

FIG. 4 is a side view of the invention of FIG. 1, as seen from the right side of FIG. 2;

FIG. 5 is a side view of the invention of FIG. 1, as seen from the left side of FIG. 2; and,

FIG. 6 is a top plan view of the invention of FIG. 1.

The canvas or fabric surface ornamentation forms part of the claimed design.

The broken lines show a mechanical fastener and forms no part of the claimed design.

1 Claim, 6 Drawing Sheets
